Primary Examiner — Stacia A Cadmus*(74) Attorney, Agent, or Firm* — Westerman, Hattori, Daniels & Adrian, LLP(57) **CLAIM**

The ornamental design for a wheel for automobile, as shown and described.

DESCRIPTION

FIG. 1 is a perspective view of a wheel for automobile; FIG. 2 is a front elevation view thereof; FIG. 3 is a right side elevation view thereof; FIG. 4 is a left side elevation view thereof; FIG. 5 is a top plan view thereof; FIG. 6 is a bottom plan view thereof; and, FIG. 7 is a partial enlarged view in the perspective thereof. The broken lines shown in the drawings illustrate portions of the wheel for automobile that form no part of the claimed design.
